(57) **CLAIM**

The ornamental design for a ceiling lamp, as shown and described.

DESCRIPTION

FIG. 1 is a top side perspective view of a ceiling lamp in a closed configuration showing our new design;

FIG. 2 is a bottom side view of the ceiling lamp in a closed configuration of FIG. 1;

FIG. 3 is a top side view of the ceiling lamp of FIG. 1 in a closed configuration;

FIG. 4 is a left side view of the ceiling lamp of FIG. 1 in a closed configuration;

FIG. 5 is a right side view of the ceiling lamp of FIG. 1 in a closed configuration;

FIG. 6 is a front side view of the ceiling lamp of FIG. 1 in a closed configuration;

FIG. 7 is a rear side view of the ceiling lamp of FIG. 1 in a closed configuration;

FIG. 8 is a bottom side perspective view of the ceiling lamp of FIG. 1 in a closed configuration;

FIG. 9 is a bottom side perspective view of the ceiling lamp of FIG. 1 in an open configuration;

FIG. 10 is a bottom side view of the ceiling lamp of FIG. 1 in an open configuration;

FIG. 11 is a top side view of the ceiling lamp of FIG. 1 in an open configuration;

FIG. 12 is a left side view of the ceiling lamp of FIG. 1 in an open configuration;

FIG. 13 is a right side view of the ceiling lamp of FIG. 1 in an open configuration;

FIG. 14 is a front side view of the ceiling lamp of FIG. 1 in an open configuration;

FIG. 15 is a rear side view of the ceiling lamp of FIG. 1 in an open configuration; and,

FIG. 16 is a top side perspective view of the ceiling lamp of FIG. 1 in an open configuration.

The broken lines are included for the purpose of illustrating unclaimed portions of the ceiling lamp and form no part of the claimed design.

1 Claim, 11 Drawing Sheets
